MANIFOLDING SET

George W. Hall, Lewiston, N. Y., assignor to
 American Sales Book Company, Inc., Niagara
 Falls, N. Y., a corporation of Delaware

Application May 19, 1937, Serial No. 143,544

2 Claims. (Cl. 282—22)

This invention relates to improvements in record supplies adapted for manifolding inscription, and with respect to its more specific features, relates to a single unitary manifolding assembly or set of record and transfer leaves attached together and having a relation of parts and characteristics adapting it particularly for use in connection with typewriters and other forms of writing machines, as well as for manual inscription, and especially adapting it for efficient separation of the record from the transfer leaves after completion of the inscription. The invention is particularly applicable to a manifolding assembly of the kind referred to, in which the record leaves have a large width or horizontal dimension, or have a width dimension substantially in excess of the height or vertical dimension measured from top to bottom of the record leaf.

One of the objects of the present invention is the provision of a practical assembly of the kind referred to, having a suitable pliability notwithstanding the stiffening effect of a binding stub which connects with the top or bottom edge of the assembly for holding the leaves of the assembly together and for piloting the leaves in manifolding relation while the assembly is being used in typewriters with cylindrical platens and in other manifolding uses.

Another object of the invention is the provision of an improved assembly of the kind referred to wherein the wide record leaves, after an inscribing operation is completed thereon, may be selectively and efficiently separated in a single operation from the transfer leaves and from the stub holding all the leaves together during the manifold inscribing operation.

Another object of the invention is the provision of an improved assembly of the kind referred to wherein the record leaves may be provided with severance lines of desired weakness for facilitating the separation of the record leaves from the transfer leaves and the stub with which the leaves are held together and for leaving smooth clean edges on said record leaves where severed, the shape and relation of parts being such as to avoid objectionable roughness at the torn edge or tendency of accidental severance at the weakened lines while the assembly is being handled.

The invention accordingly comprises the features of construction, combinations of elements, and arrangement of parts which will be exemplified in the construction hereinafter described and the scope of the application of which will be indicated in the claims.

The nature and objects of the invention will be understood more fully by reference to the following detailed description together with the accompanying, in which:

Fig. 1 is a perspective view of a unitary mani-

folding assembly of superposed leaves, embodying the invention;

Fig. 2 is a diagrammatic end elevation of the unit of Fig. 1, on a larger scale than Fig. 1, showing exaggerated vertical spacings between the superposed leaves, for more clearly displaying the structure of the assembly; and

Fig. 3 is a perspective partially diagrammatic view of fragments of leaves of the Fig. 1 unit to the left of the line 3—3, Fig. 1, showing on an enlarged scale the superposed relation of the leaves, but for clearness of disclosure, omitting certain parts of the assembly, and showing exaggerated vertical spacings between the superposed leaves for clearness of disclosure.

Referring now to the drawing, Fig. 1 illustrates a unitary manifolding assembly or set, having a rectangular form, with the longer dimension running horizontally or in the width direction and the shorter dimension running in the vertical or height direction. The assembly consists of the superposed leaves 10, 11, including two or more record leaves 10 and a transfer leaf 11 interleaved between each pair of adjacent record leaves. The transfer leaves 11 have transfer material 12, Fig. 3, on their undersurfaces, so that by inscribing on the upper surface of the assembled unit, an original copy is produced on the uppermost record leaf 10 and a duplicate copy is produced on each of the lower record leaves 10.

The leaves 10, 11, Fig. 1, have a large width dimension from the side edge 13 to the side edge 14 in a direction parallel to one of the edges 15, 16, and have a relatively short height dimension measured from the top edge 15 to the bottom edge 16 in a direction parallel to the edges 13, 14 and perpendicular to the width dimension. The uppermost record leaf 10, as illustrated, may include a form suitable for use as a bank check 15 with a stub 13 detachable therefrom at the weakened severance line 17. It will be understood, however, that the leaf 10 may be adapted by its printing or other indicia thereon for various other uses, such as a receipt, or as a broker's form for identifying securities bought or sold for a customer, or as a wide, short form for some other purpose, such leaves usually having a width dimension of approximately two or more times the height dimension.

Each leaf 10, 11 has a stub 18 projecting outwardly therefrom and connecting with and extending along the bottom edge 16 and preferably centralized midway between the ends of the edge 16. It will be understood that in certain cases the stub 18 may be located on the top edge 15 rather than on the bottom edge 16, and that in some cases the position of the stub 18 may depart from the central position, as in Fig. 1, for example, if it be assumed that the detachable portion 13 be separated at the weakened line 17.

from the check portion 15. The stub 18 is preferably of such a length that, when substantially flat, it may be grasped readily at its approximate extremities by a single unaided hand in a single operation for reasons which will appear herein-after.

In the case illustrated, where the top leaf 10 is used as a bank check 15 with the detachable portion 13, the stub 18 may be less than one-half 10 as long as the edge 16, representing the width dimension of the leaves, and similarly in the case of most of the other wide forms referred to, the length of the stub along the edge with which it connects is approximately one-half or 15 less times the length of said edge. The stubs 18 are in superposed relation as shown more clearly in Figs. 2 and 3, and are fastened together by the adhesive binding material 19, Fig. 2, between the adjacent surfaces of the stubs 18, thus 20 providing a binding stub 20 for holding the record and transfer leaves 10, 11 in manifold registration. In most cases, it is preferable to make the stub 18 as long as possible consistent with the hand-grasp limitation, referred to above, in 25 order that the stub may exert a maximum pilot-ing influence in maintaining the leaves in manifold registration. The leaves 10, 11 of the assembly are preferably free from any connection therebetween, except by way of the stub 20.

30 A weakened severance line 21 is provided in each record leaf 10 for defining a line of separation between the leaf and its connected stub 18, as shown in Fig. 3, whereas each transfer leaf 11 has an unbroken and unweakened connection with its stub 18 in the region corresponding with that of the severance line 21 of the record leaves 10. The severance line 21 is located close to or in line with the adjacent edge 16 of the leaf 10, so that when the record leaf 10 is 35 severed from its stub 18, the resulting torn edge of leaf 10 provides an exact or nearly exact continuation of the straight edge 16. Furthermore, any roughness left at the torn edge along the line 21 is limited in extent to the length of the stub 18 and does not extend along the entire 40 length of the edge 16.

Fig. 3 omits a showing of the fastening means 19 in order to illustrate more clearly the superposed relation of the severance lines 21 and the 45 unweakened connections between each transfer leaf 11 and its stub 18 in the region corresponding with that of the severance line 21 in each record leaf 10.

Each record leaf 10 has a marginal portion 50 along the edge 15, remote from the stub 18 and the severance line 21 and extending outwardly beyond the nearest adjacent edge of the transfer leaf 11 as clearly shown in Fig. 2, these marginal portions being in superposed relation with each 55 other, and in off-set relation to the adjacent edges of the transfer leaves 11, and constituting a selective grip formation for facilitating separation of the record leaves 10 from the stub 20 and the transfer leaves 11.

60 When using the assembly in a typewriter with a cylindrical platen, the top edge 15 is first fed into the typewriter in a direction parallel to the vertical edges 13, 14, and after making the desired inscriptions with the typewriter, the feeding movement of the assembly is continued in the same direction until the assembly has been fed entirely through the typewriter with the edge 16 and the stub 20 trailing behind the edge 15. After all of the necessary inscriptions have been 65 completed, the selective grip formation along the

edge 15 is grasped in one hand while the stub 20 is grasped in the other hand, and a tearing force is exerted along the weakened line 21. The record leaves 10 may thus be quickly and easily selectively severed in a single operation from the binding stub 20 and at the same time selectively and cleanly stripped from the transfer leaves 11.

Throughout the separating operation, the transfer leaves 11 remain connected with the 10 stub 20 because of their unweakened connection with the stub and the fact that no substantial tearing force is exerted on the transfer leaves while the assembly is grasped exclusively at the edge 15 grip formation and at the stub 20. 15

The whole separating operation may be accomplished with the quickness of the snap of the fingers, since the position of each hand is fixed relatively to the assembly and does not need to be shifted, as would be necessary for positive severance of a binding stub connecting along the edge 16 for a longer distance than could be spanned by a single hand grasp. Any shifting of the hand to successive tearing positions, not only introduces delay in the tearing operation 25 but also increases the tendency toward faulty tearing when the tearing of a record leaf 10 hidden below the upper transfer leaf 11 has stopped at a different point from the tearing of the top leaf 10 and is not adapted to be continued properly by the tearing force applied by a successive position of the hand grasp intended to continue the tearing of the top leaf 10. 30

It will be noted that the selective grip formation provided by offsetting the record leaves with 35 reference to the carbon or transfer leaves as shown, is preferably positioned directly across the manifolding assembly from the binding stub 20.

In other words, in the embodiment shown the selective grip formation has at least a part 40 thereof centralized at one of the longer marginal parts of the assembly as is the binding stub 20 at the opposite edge. This is an advantageous arrangement because at the moment that the record leaves are snapped from their interleaved 45 relation with the carbons and detached from the binding stub, the stresses required for such detachment will be transmitted through the several leaves directly thereacross and substantially at right angles to the major dimension of the 50 assembly. This assures a complete and clean severance of the record leaves from the binding stub at a single quick pull, and the danger of tearing or mutilating the leaves otherwise than along the weakened severance lines 21 is avoided. 55 Also, it is to be noted that the weakened severance lines 17 providing the detachable end coupons, lie outside of the binding stub 20 and for this reason the danger of accidentally tearing the leaves along these lines 17 at the time of severance of the leaves from the stub 20 is wholly avoided. Also, this arrangement of the weakened lines 17 provides a convenient arrangement 60 whereby anyone of the end coupons may be conveniently severed from the assembly prior to detachment of the record leaves from the binding stub. The coupons may thus be very readily detached either before or after severance of the record leaves from the binding stub. 65

For the reasons already mentioned, it will be 70 observed that the predetermined width dimension of the leaves, parallel to the edge 16, is so large as to prevent the assembly, when substantially flat, from being grasped at the approximate extremities of the width dimension by a single 75

unaided hand in a single operation, and it would consequently not be possible to utilize a binding stub running along the full width of the assembly and obtain the advantages of the stub 20, as referred to above.

The provision of the stub 20 on one of the long horizontal edges 15 or 16, with the predetermined length of the stub limited to less than that of the horizontal edge with which it connects, is particularly advantageous in connection with the inscription of the assembly in a typewriter with a cylindrical platen, and in connection with the operation of severing the record leaves 10 from stub 20 and the transfer leaves 11, and in other connections.

When feeding the assembly through a typewriter with a cylindrical platen and adjusting the position of the assembly in the typewriter, the centralized stub 20 exerts a relatively balanced piloting action on the leaves 10, 11, and is much more pliable than a stub extending along the full length of the edge 15 or 16. Owing to the greater exposure of such a full length stub to obstruction in the typewriter, and owing to the greater stiffness of such a stub and the effect of the severance line in abruptly reducing the stiffness of the assembly at that line, there is considerably more tendency for one end of the full length stub to catch in the typewriter and considerably more tendency for accidental severance of the full length stub and of resultant clogging of the typewriter or of mutilating the record leaves in the typewriter than with an assembly having the short stub 20.

Location of the short stub 20 on one of the long horizontal edges 15 or 16, simplifies the problem of providing a suitable severance line 21, since the tearing operation is simplified as explained above, and the conditions necessary to furnish satisfactory severance, without objectionable tendency of accidental severance, are more readily attainable over a wide range of strengths of severance lines than in the case of a longer severance line. Consequently the severance line may be made weaker than is practicable with a binding stub extending the full length of the edge 15 or 16, and a smoother, cleaner edge may thus be obtained at the line 21.

A further advantage of providing the short stub 20 on the long horizontal edge 15 or 16, is that the stub adds nothing more to the already burdensome length of the width dimension of the assembly, and thus avoids the need of a larger and more costly typewriter for accommodating a wider assembly resulting from placing the binding stub on one of the edges 13 or 14, and avoids the corresponding need of providing twice as much additional space for accommodating the back-and-forth movement of the typewriter carriage. Furthermore, the stub 20, as disclosed, avoids the very unsatisfactory unbalanced piloting action of a stub at one of the edges 13 or 14 of the leaves of the assembly.

It will be understood that the selective grip formation may be formed in various ways other than that of the illustrative form disclosed above. It will also be understood that certain other changes may be made in the record and transfer leaves and in the assembly thereof, without departing from the invention disclosed herein, and that the scope of the invention should not be limited to the particular embodiment described herein and shown in the accompanying drawing, as illustrative of the invention.

Having described my invention, what I claim

as new and desire to secure by Letters Patent is:

1. A manifolding assembly including, in combination, a plurality of superposed leaves, including a plurality of record leaves and at least one transfer leaf in transfer relation between two of said record leaves, said record and transfer leaves being substantially longer in one direction than in a direction perpendicular thereto, each said record and transfer leaf having a stub connecting therewith along one of the longer edges of the leaf and positioned at the same edge of said assembly, said stub being substantially shorter than said longer edge in the direction of said edge, thus providing interleaved record and transfer leaf portions for receiving transfer inscriptions and protruding in the direction of the major leaf length beyond said stubs, means for fastening the stubs together to provide an assembly binding stub for holding the leaves of the assembly together, said binding stub being relatively short as compared to the major assembly dimension and terminating within said protruding leaf portions, each said record leaf having a weakened severance line for defining a line of separation between the leaf and said binding stub, said severance lines terminating short of said protruding leaf portions, certain of said record leaves having marginal portions remote from said binding stub extending in offset relation beyond the adjacent edge of said transfer leaf, and providing a selective grip formation for facilitating the selective separation of said record leaves from said binding stub and said transfer leaf.

2. A manifolding assembly including, in combination, a plurality of superposed leaves, including a plurality of record leaves and at least one transfer leaf in transfer relation between two of said record leaves, said record and transfer leaves being substantially longer in one direction than in a direction perpendicular thereto, each said record and transfer leaf having a stub connecting therewith along one of the longer edges of the leaf and positioned at the same edge of said assembly, said stub being substantially shorter than said longer edge in the direction of said edge, thus providing interleaved record and transfer leaf portions for receiving transfer inscriptions and protruding in the direction of the major leaf length beyond said stubs, means for fastening the stubs together to provide an assembly binding stub for holding the leaves of the assembly together, said binding stub being relatively short as compared to the major assembly dimension and terminating within said protruding leaf portions, each said record leaf having a weakened severance line for defining a line of separation between the leaf and said binding stub, said severance lines terminating short of said protruding leaf portions, certain of said record leaves having marginal portions remote from said binding stub extending in offset relation beyond the adjacent edge of said transfer leaf, and providing a selective grip formation for facilitating the selective separation of said record leaves from said binding stub and said transfer leaf, said selective grip formation having its grip portion positioned at a marginal part of the assembly directly opposite to said short assembly binding stub whereby severance of the record leaves from the stub may be effected by a single quick pull directed along a line substantially perpendicular to the severance lines.
